UNITED STATES PATENT OFFICE.

EDWIN G. HINES, OF DRUMS, PENNSYLVANIA.

MILK-BOTTLE RECEPTACLE.

Application filed January 24, 1927. Serial No. 163,232.

This invention relates to special receptacles and more particularly to a receptacle in which a milk bottle may be placed and, if desired, the receptacle locked. At the present time it is customary to place empty bottles upon a porch or in an areaway for collection by the milk driver when delivering filled bottles and it often happens that empty bottles are accidentally broken or filled bottles stolen and also very often dust and dirt will accumulate upon the rim of a filled bottle and not properly washed off before the bottle is opened or a filled bottle will become contaminated or knocked over and broken by an animal, such as a dog or a cat attempting to obtain access to the milk within the bottle.

Therefore, one object of the invention is to provide a receptacle in which an empty bottle may be placed for removal by the milk driver who substitutes a filled bottle thereby preventing either the empty or the filled bottle from being accidentally broken and in addition preventing the filled bottle from becoming spoiled by dust or reached by animals and, if the cover of the receptacle is locked, prevented from being taken by unauthorized persons.

Another object of the invention is to provide the receptacle with ventilating openings so that air may circulate through the receptacle when closed.

Another object of the invention is to so form the bottom of the receptacle that a bottle placed therein will be prevented from closing a ventilating opening formed in the bottom.

The invention is illustrated in the accompanying drawing, wherein

40 Figure 1 is a view showing the improved receptacle in side elevation;

Fig. 2 is a longitudinal sectional view through the receptacle taken on the line 2—2 of Fig. 1;

45 Fig. 3 is a transverse sectional view taken on the line 3—3 of Fig. 2, and

Fig. 4 is a perspective view of a resilient ring forming a portion of a false bottom.

The receptacle is provided with a hollow body portion 1 which is preferably of a cylindrical shape and may be of any height and diameter desired according to the number of bottles which it is intended to hold. The rear portion of the body which is formed with a flat face is secured against the forward face of a hanger or backing

plate 2 which is of greater height than the body and extends above the same, as shown in Figs. 1 and 2. The upwardly projecting end portion of the hanger is preferably shaped to define a head 3 having an opening 4 formed therein through which a nail or other suspending device carried by a support may be passed to suspend the receptacle in an elevated position or the head may be formed with several smaller openings to receive screws or bolts, by means of which the receptacle may be permanently attached to a wall or door frame at such an elevation that it may be easily reached by the milk driver but inaccessible to a dog, cat or other animal. By referring to Fig. 2 it will be seen that, when forming the body with a flat face to engage the forward face of the backing plate, a longitudinally extending slot 5 is formed through which a portion of the forward face of the backing plate is exposed. This portion of the backing plate carries a clip 6 formed of resilient wire having its arms suitably anchored to the backing plate and projecting upwardly. This clip is intended to carry a card or other record sheet 7 upon which a record may be kept of the amount of milk left every day during a week, month or any other period of time. The bottom 8 of the body is securely fastened therein in any desired manner and is formed with a ventilating opening 9 which occupies the major portion of its area and is covered by a false bottom or shield 10. The false bottom or shield is preferably formed of sheet metal having perforations 11 formed therein and its marginal portions bent downwardly to form a depending annular rim or flange 12 which rests upon the upper or inner face of the bottom and holds the false bottom or shield in spaced relation to the opening 9. A filtering sheet 13 formed of loosely woven fabric or any other suitable material fits 100 against the under face of the shield and is held in engagement therewith by an expanding ring 14 formed of a strand of resilient wire. The ends of the strand from which the expanding ring is formed are bent to 105 provide fingers 15 which may be grasped so that the ring may be contracted and easily inserted or removed from the shield. When in place, the ring expands and has gripping engagement with the depending 110 rim or flange and securely holds the filtering sheet in place but permits it to be easily re-

moved in order that it may be cleaned or a new one substituted. Adjacent its upper end the walls of the body are formed with side openings 15 through which air entering the body through the lower opening may pass out of the body, and these side openings are covered by sheets of woven fabric 16 which serve to exclude dust and are held in place by rings 17 formed of sheet metal 5 and secured against the walls about the openings by screws or other suitable fasteners 18. The cover 19 which closes the open upper end of the body is connected with the backing plate by cooperating hinge 10 members 20 so that it may be swung upwardly from a closed to an open position and may be provided with a suitable lock engaging a keeper carried by the body or provided with a hasp adapted to engage a 15 keeper through which a padlock may be passed.

When the receptacle is in use, it is secured against a door frame or wall at such height that it cannot be reached by animals 20 and an empty milk bottle placed in the receptacle will not be liable to be accidentally knocked over and broken. When the milk man removes the empty bottle and replaces it with a filled one, the cover is closed and if 25 provided with a lock it may be securely fastened. The filled bottle placed in the receptacle will be protected from being contaminated by animals attempting to reach the milk and also prevent it from being accidentally knocked over and broken with resulting wasting of the milk. Since the bottle rests upon the false bottom, it will be prevented from closing the opening 8 formed in the bottom 7 and air may freely pass 30 through the opening 8 into the body and upwardly about the milk bottle disposed therein and out through the side openings 15. This provides a circulation of air through the receptacle and prevents the milk from 35 being spoiled by the effect of warm air which would accumulate in a closed and unventilated receptacle. A number of small openings 21 have been provided about the walls of the body close to its upper end so that air 40 in the upper portion thereof which does not pass out through the openings 15 may escape. When the milk man places one or more bottles in the receptacle, he enters the amount delivered upon the card 6 which is 45 verified by the person removing the bottles and by this means a record may be kept of the amount of milk delivered each week or month.

Having thus described the invention, I 50 claim:

1. A receptacle comprising a hollow body open at its upper end and having a bottom formed with an air inlet opening, a removable perforated false bottom in said body covering the ventilating opening, a dust excluding sheet carried by said false bottom and removably held against its under face, the upper portion of the walls of said body being formed with air outlet openings, dust excluding covers for the air outlet openings, 65 and a cover for the open upper end of said body movable into and out of closing relation thereto.

2. A receptacle of the character described comprising a hollow body open at its top 75 and having a bottom formed with a ventilating opening occupying the major portion of its area, a false bottom in said body consisting of a perforated disk having its marginal portion bent downwardly to form a flange resting upon the bottom of said body adjacent the walls thereof, a dust excluding sheet fitting against the under face of said disk, an expanding ring engaging said flange and sheet to hold the sheet against said disk, 85 the upper portion of the walls of said body being formed with ventilating openings, dust excluding covers for the upper ventilating openings, and a closure for the upper end of said body movable into and out of closing relation thereto.

3. A receptacle of the character described comprising a hollow body open at its top and having a bottom formed with a ventilating opening occupying the major portion of 95 its area, a false bottom in said body consisting of a perforated disk having its marginal portion bent downwardly to form a flange resting upon the bottom of said body adjacent the walls thereof, a dust excluding sheet 100 fitting against the under face of said disk, an expanding ring engaging said flange and sheet to hold the sheet against said disk, and a cover for the open upper end of said body movable into and out of closing relation 105 thereto.

4. A receptacle of the character described comprising a hollow body open at its top, a bottom for said body having an opening formed therein, a perforated disk in said body having a depending marginal flange resting upon said bottom, a filtering sheet, a resilient retaining ring disposed within the confines of said flange and holding said sheet against the under face of said disk, 110 and a cover movable into and out of closing relation to the open top of said body.

In testimony whereof I affix my signature,

EDWIN G. HINES. [L.S.]
